UNITED STATES PATENT OFFICE.

FLINT W. WRIGHT AND PHILLIP H. COMMERFORD, OF BINGHAMTON, NEW YORK.

AUTOMATIC PIANO-PLAYER TREADLE.

No. 883,068.

Specification of Letters Patent. Patented March 24, 1908.

Application filed March 18, 1907. Serial No. 363,065.

To all whom it may concern:

Be it known that we, FLINT W. WRIGHT and PHILLIP H. COMMERFORD, citizens of the United States, and residing at Binghamton, in the county of Broome and State of New York, have invented a certain new and useful Improvement in Automatic Piano-Player Treadles, of which the following is a specification.

Our invention is an improvement in the class of foldable bellows-operating treadle attachments for self-playing pianos, also for organs or melodions.

The improvement pertains to the construction, arrangement, and combination of parts hereinafter described and claimed.

In the accompanying drawings, Figure 1 is a side view of our treadle mechanism in operative position, a portion of the piano case being shown in section. Fig. 2 is a similar elevation and section, the treadle mechanism being shown folded within the piano case. Fig. 3 is a perspective view of the main frame of the pedal attachment.

There are two foot-boards or pedals proper, 17, hinged at 18 to a frame comprising a bar 19 having feet 20, and such frame is pivotally attached to the lower front portion of the piano case at 22 by means of parallel rods 21, which are rigidly connected—see Fig. 3—by a transverse bar 26 at points located a short distance from the pivots 22. As shown, this bar is dropped, or hangs below the parallel rods 21, for a purpose that will be presently explained.

The means of operative connection between each of the two bellows 16 and each of the pedals 17 is a lever arm formed of two parts 24, 24^a, hinged together and provided with a shouldered or rule joint at 24^b. The inner end 23 of part 24^a is bent practically at a right angle and secured to the bellows 16, while the corresponding end of part 24 carries a roller 25, that serves to reduce friction with the pedals 17 with which it works in contact.

The rule joint 24^b is so constructed as to support the part 24 in alinement with part 24^a, when the treadle attachment is lowered to position for use, as shown in Fig. 1, but it permits said part 24 to fold inward to a ver-

tical position, or at right angles to the part 24^a, when the attachment is folded into the piano case, as in Fig. 2.

The dropped cross bar 26 before described as an attachment of the parallel rods performs an important function in the folding operation, in that it serves to engage and throw back the foldable parts 24 of the jointed bellows arms and thus carry them up to vertical position and hold them in such position within the piano case until the treadle attachment shall be again drawn out into position for use. The drop in the bar 26 is necessary in order to accommodate the parts 24 and their rollers 25.

It will be understood that the jointed foldable arms 24 are pushed forward and downward (from the vertical position, Fig. 2, to the inclined position, Fig. 1) by the pedals 17 when the latter are pulled outward and downward for use. Thus the transverse bar 26 folds the parts 24 inward and the pedals 17 pull them out again.

When the jointed lever arm is out of use as in Fig. 2, the bellows is held distended so that the flexible material composing its sides is stretched and hence it is not liable to crack as if when folded and creased.

What we claim is:

The combination with the piano case and bellows arranged therein, of the treadle attachment comprising a frame hinged to said case, pedals hinged to the frame, jointed arms attached to the bellows, their front ends being foldable inward and provided with a rule joint which renders them self-supporting in position for co-action with the pedals, the aforesaid frame having feet and the parallel rods 21 having a transverse connecting bar 26 arranged a short distance from the hinges of the rods for engagement with the jointed foldable parts of the jointed arms, whereby said parts are raised and held in folded position in contact with the pedals when the attachment is folded into the case as shown and described.

FLINT W. WRIGHT.

PHILLIP H. COMMERFORD.
